LUBRICATING BOX

Castor M. Vigo, Tampa, and René R. Nadal,
Archer, Fla.

Application April 30, 1946, Serial No. 665,973

4 Claims. (Cl. 308—85)

1

This invention relates to a lubricating box, and more particularly to such a box adapted for positioning at the extremities of axles for railroad cars and the like.

A primary object of this invention is the provision of an improved lubricating box characterized by the absence of stuffing or packing, and wherein a continuous circulation of the lubricant is provided insuring ready lubrication of the axle or shaft at all times.

An additional object of this invention is the provision of a rotatable ring secured to the axle or shaft, and adapted to lift the oil from the lower portion of the lubricating box to the upper portion thereof, including means whereby the oil is redirected to the extremity of the axle or shaft.

Still another object of the invention is the provision of an improved rotating obturator for the redirection and recirculating of oil into the lubricating chamber, and a further closure member adapted to insure an effective seal against the escape of any lubricant along the shaft or axle.

A still further object of the invention is the provision of such a device characterized by means whereby the oil is returned from the rotating ring adapted to elevate it above the shaft to the top of the shaft, with a minimum of difficulty in effort.

Still another object of the invention is the provision of improved means for adjusting the relative tightness of the seal of the outer obturator in order to positively preclude the escape of oil or similar lubricating fluid thereover.

Still other objects reside in the combinations of elements, arrangements of parts and features of construction, all as will be more fully pointed out hereinafter and disclosed in the accompanying drawings, wherein there is shown a preferred embodiment of this inventive concept.

In the drawings:

Figure 1 is a vertical longitudinal cross section showing one form of lubricating box embodying features of the instant invention.

Figure 2 is a sectional view taken substantially along the line 2—2 of Figure 1, as viewed in the direction indicated by the arrows, certain portions thereof being shown in plan.

Similar reference characters refer to similar parts throughout the several views of the drawings.

The lubricating box of the instant invention is comprised of complemental upper and lower half-sections 10 and 11, respectively, provided with extending lugs or flanges 12 having aligned apertures 13 therein, through which extend bolts 14, 55 lugs 32^a positioned in channels 32^b cut in the

2

holding the upper and lower halves in related assembly to form a unitary structure having an internal lubricating fluid reservoir 15. The upper half-portion 10 is provided with a longitudinally extending channel 16, in which is adapted to be seated a supporting spring of a vehicle, such for example as a railway car.

Journaled for free rotation within the chamber 15 formed by the halves 10 and 11 is an axle generally indicated at 17, upon which are mounted conventional wheels (not shown). An obturator is formed for final sealing of the lubricant within the reservoir 15 by means of complemental upper and lower ring-like segments, including brass segments 18 and leather segments 19, adapted to bear against the shaft of the axle 17. The compression of the leather segments 19 may be readily varied, as by means of screws 20 extending through suitable oppositely disposed apertures in the brass segments 18 and 11, respectively, and carrying lock nuts 21. Positioned axially outwardly from the segments 18 and 19 is a second obturator 22, which is comprised of a beveled flange facing the chamber 15, secured to and rotatable with the axle 17 within a groove 23 formed annularly within the housing. The lower portion of the groove 23 includes a channel 24, extending downwardly to a port 25 in the lower section of the housing, through which oil caught by the rotating ring 22 may return to the chamber 15. A depression 26 is formed at a point adjacent the port 25 for the accommodation of such fluid.

Positioned interiorly of the rotating ring 22 is an elevator ring 27 for lubricant, of a configuration generally similar to the ring 22, but larger in diameter, and provided with a beveled edge 28. The elevating ring 27 is adapted for free rotation within the chamber 15 with the axle 17.

The elevator ring 27 is rotatable in an annular groove 29 in the housing, parallel to the annular groove 23 and from whose upper part a declining oil return passage 30 opens through the top of the chamber 15. The upper end of the passage 30 is also in communication with a filling opening 31, through which oil can be introduced into the chamber 15. The filling opening 31 is closed by a plug member including a brass wiper 32 and a top piece 33, the wiper member 32 being provided with an angularly disposed lower face 34 adapted normally to be held in abutting relation with the periphery of the ring 27, in such manner as to correspond with the bevel thereof. The plug member includes extending

sides of aperture 31 to insure proper alignment of the wiper member 32. It will thus be seen that the elevating ring 27 is adapted to lift oil during the rotation thereof from the lower portion of the chamber or space 15 to the top thereof, which oil or similar lubricant is wiped off of the beveled edge of the ring into the channel 38 and flows downwardly therewithin.

Positioned over the top of the axle 17 is a brass journal bearing 35 provided with tongues 36 engaging in suitable channels or grooves 37 in the side walls of the upper member 10, in such manner as to preclude the rotation thereof with the axle, and which journal brass is provided with channels 38 in the top thereof for the accommodation of lubricant. The channels are provided with apertures or bores 39 which extend entirely through the member 35 into contact with the upper surface of the axle 17, and permit the passage of fluid therethrough to the axle.

It will thus be seen that oil passed through the channel 38 falls to the upper surface of the journal brass 35, and is thence conveyed through the channels 39 to the axle, to afford an effective lubrication thereof. As previously described, it will be seen that as the lubricating fluid falls off the axle into the lower portion of the chamber 15, the same is raised by the elevating ring 27 and wiped off by the brass member 32, to re-fall through the channel 38 and re-lubricate the device continually.

If desired, the lower member 11 may be provided with a port or aperture 40, provided with a closure member 41 secured in position, as by screws 42, through which access may be had to the interior of the device for cleaning purposes or the like.

From the foregoing it will now be seen that there is herein provided an improved lubricating box characterized by the complete absence of the customary stuffing or packing, which insures a relatively continuous flow of lubricant to the axle or shaft, and which is reliable and efficient in operation, and relatively simple and inexpensive to manufacture and assemble, which accomplishes all the objects of this invention, and others, including many advantages of great practical utility and commercial importance.

While in the foregoing this device has been described as particularly adapted for use with railway axles, or the like, it is to be understood that it is equally applicable to any axle requiring the use of a lubricating box, or any similar rotating shaft.

As many embodiments may be made of this inventive concept, and as many modifications may be made in the embodiment hereinbefore shown and described, it is to be understood that all matter herein is to be interposed merely as illustrative and not in a limiting sense.

We claim:

1. In a journal box, a lubricant containing housing having an end formed with an opening, an axle extending through said opening and having a bearing portion within said housing, the interior of said housing being formed with axially spaced first and second annular channels surrounding said axle, a first declining lubricant return passage leading from said first annular channel into the lower part of said housing, said second annular channel being open to the lower part of the interior of said housing, a second outwardly declining lubricant return passage in the upper part of said housing above said axle and located adjacent to said end of the housing, said

second passage having its upper end in communication with the upper part of said second annular channel and its lower end in communication with the upper part of the interior of said housing above said bearing portion of the axle, said axle having first and second rings located between said housing end and the bearing portion of the axle, said first and second rings being axially spaced from each other and arranged to work closely in said first and second annular channels, respectively.

2. In a journal box, a lubricant containing housing having an end formed with an opening, an axle extending through said opening and having a bearing portion within said housing, the interior of said housing being formed with axially spaced first and second annular channels surrounding said axle, a first declining lubricant return passage leading from said first annular channel into the lower part of said housing, said second annular channel being open to the lower part of the interior of said housing, a second outwardly declining lubricant return passage in the upper part of said housing above said axle and located adjacent to said end of the housing, said second passage having its upper end in communication with the upper part of said second annular channel and its lower end in communication with the upper part of the interior of said housing above said bearing portion of the axle, said axle having first and second rings located between said housing end and the bearing portion of the axle, said first and second rings being axially spaced from each other and arranged to work closely in said first and second annular channels, respectively, a wiper mounted in the upper end of said second lubricant return passage and engaging the periphery of said second ring whereby lubricant on said second ring is wiped to subside through said second passage to lubricate said axle bearing portion.

3. In a journal box, a lubricant containing housing having an end formed with an opening, an axle extending through said opening and having a bearing portion within said housing, the interior of said housing being formed with axially spaced first and second annular channels surrounding said axle, a first declining lubricant return passage leading from said first annular channel into the lower part of said housing, said second annular channel being open to the lower part of the interior of said housing, a second outwardly declining lubricant return passage in the upper part of said housing above said axle and located adjacent to said end of the housing, said second passage having its upper end in communication with the upper part of said second annular channel and its lower end in communication with the upper part of the interior of said housing above said bearing portion of the axle, said axle having first and second rings located between said housing end and the bearing portion of the axle, said first and second rings being axially spaced from each other and arranged to work closely in said first and second annular channels, respectively, a wiper mounted in the upper end of said second lubricant return passage and engaging the periphery of said second ring whereby lubricant on said second ring is wiped to subside through said second passage to lubricate said axle bearing portion, a perforated journal brass in the upper part of said housing with which said axle bearing portion is engaged and onto which lubricant subsiding in said second passage flows.

4. In a journal box, a lubricant containing

housing having an end formed with an opening, an axle extending through said opening and having a bearing portion within said housing, the interior of said housing being formed with axially spaced first and second annular channels surrounding said axle, a first declining lubricant return passage leading from said first annular channel into the lower part of said housing, said second annular channel being open to the lower part of the interior of said housing, a second outwardly declining lubricant return passage in the upper part of said housing above said axle and located adjacent to said end of the housing, said second passage having its upper end in communication with the upper part of said second annular channel and its lower end in communication with the upper part of the interior of said housing above said bearing portion of the axle, said axle having first and second rings located between said housing end and the bearing portion of the axle, said first and second rings being axially spaced from each other and arranged to work closely in said first and second annular channels, respectively, a wiper mounted in the upper end of said second lubricant return passage and engaging the periphery of said second ring

whereby lubricant on said second ring is wiped to subside through said second passage to lubricate said axle bearing portion, said housing being formed with a filling opening communicating with the upper end of said second lubricant passage, said wiper comprising a plug portion fitting said filling opening and a wiper portion engaging said second ring.
